(57) **CLAIM**

The ornamental design for a dispensing device, as shown and described.

DESCRIPTION

FIG. 1 is a left side perspective view of the dispensing device; FIG. 2 is a right side view of the dispensing device; FIG. 3 is a front side view of the dispensing device; FIG. 4 is a left side view of the dispensing device; FIG. 5 is a rear view of the dispensing device; FIG. 6 is an enlarged top view of the dispensing device; FIG. 7 is an enlarged bottom view of the dispensing device; FIG. 8 is an enlarged bottom view of a first variant of FIG. 7 of the dispensing device; and, FIG. 9 is an enlarged bottom view of a second variant of FIG. 7 of the dispensing device.

The broken lines shown throughout the views of the dispensing device are for environmental purposes only and form no part of the claimed design.

1 Claim, 9 Drawing Sheets
